UNITED STATES PATENT OFFICE.

OWEN JAMES FAY, OF CHICAGO, HARRY TOBIAS HEIMBERGER, OF RIVERSIDE, AND EMERSON PUGH, OF CHICAGO, ILLINOIS, ASSIGNEES TO WESTERN ELECTRIC COMPANY, INCORPORATED, OF NEW YORK, N. Y., A CORPORATION OF NEW YORK.

HEATING DEVICE.

Application filed December 23, 1927. Serial No. 242,046.

This invention relates to a heating device, and more particularly to an electrically heated soldering iron.

The object of this invention is to provide an improved heating device of simple and practical construction which permits of a quick and easy assembly or convenient replacement of parts thereof.

A preferred embodiment of the invention consists of an electrically heated soldering iron, wherein a unitary replaceable double helix heating element insulated from and surrounding a solid heat conducting core has reinforced wire terminals passing through slots in a cap and through separated longitudinal passageways in a stem insulator. The ends of the heating element are attached to connectors on opposite sides of an insulating strip which engages a slot in the end of the stem insulator and is fastened in a handle by a slotted sleeve. The connectors extend through and terminate in the end of the handle and are engaged by a quickly detachable electrical contact socket which is enclosed by a retaining cap threaded on the end of the handle.

Other objects will appear more clearly from the following detailed description of one embodiment of the invention, taken in connection with the accompanying drawings, in which

Fig. 1 is a longitudinal elevation, partly in section, of a soldering iron embodying the features of the invention;

Fig. 2 is a sectional view taken on lines 2-2 of Fig. 1;

Fig. 3 is an enlarged cross-sectional view taken on lines 3-3 of Fig. 2;

Fig. 4 is an enlarged cross-sectional view taken on lines 4-4 of Fig. 2;

Fig. 5 is an enlarged fragmentary detail view of the resistor winding showing the reinforced wire terminals thereof, and

Fig. 6 is an enlarged fragmentary perspective view disclosing a means for locking the metal shell encasing the heating unit to the stem assembly of the handle.

Referring now to the drawings wherein like reference numerals refer to similar parts throughout the several views, the numeral 10 designates a heating element of any suitable high resistance electrical conducting material formed into a helix with a straight lead 11 on each end. The helically formed re-

sistance wire 10 is wound in a loop over a 55 helically grooved cylinder 12 constructed of any suitable refractory insulating material, starting around a protruding post 13 at the forward end of the refractory cylinder 12 as illustrated in Fig. 1. The helices are so 60 spaced that they are out of contact with each other, thus preventing a short circuit which would render part of the resistor ineffective to generate heat. In order to strengthen the leads and to increase their 65 conductivity thereby minimizing the generation of heat in the leads, three extra wires are inserted a short distance inside the helix and are twisted with a lead to form a reinforced stranded terminal. This feature 70 assists in keeping the handle from becoming hot since the reinforced leads having a lowered resistance do not generate any appreciable amount of heat. The leads 11 of the resistor 10 are threaded through apertures 75 14-14 in protruding portions 15 diametrically opposite each other at the upper end of the insulating cylinder 12 and then through holes 16 to the interior of the insulating cylinder 12. From the inside of the insulating 80 cylinder 12 the leads 11 are passed through slots 20 into a substantially rectangular shaped depression 25 in an insulating cap 21 and from there through separated longitudinal passageways 22 in an insulating stem 85 of refractory material 23 having a substantially rectangular end 24 which fits into the substantially rectangular depression 25 in the cap 21 and is thus interlocked with the cap. The other end of the stem insulator 23 90 is provided with a rectangular slot 30 into which an insulating strip 31 fits carrying a connector bar 32 on either side and having screws 33-33 by means of which the leads 11 of the resistor 10 are secured thereto. The 95 connectors are crimped over the edges of the strip 31 and in addition are secured by the screws 33 and an insulating band 34, and they extend out of and beyond the end of a wooden handle 35 so that electrical supply 100 terminals 36 in a socket 37 can be engaged with the connectors 32. The socket terminals may be connected through a cord 38 to a suitable source of electrical energy. A detachable retaining cap 40, which may 105 be of any suitable metal, threaded on the handle 35 is adapted to rigidly maintain the electrical supply socket 37 in contacting po-

sition. The retaining cap carries a hard rubber or fiber washer 41 through which the cord 38 passes and the washer 41 abuts with a clamp 42 which firmly grips the electrical supply cord and relieves the terminals 36 in the socket from strain. That is, if the electrical supply cord 38 is subjected to a longitudinal pull, the strain is taken up by the clamp 42 as it bears against the washer 41 held in place by the cap 40, thereby preventing the cord from being torn from the terminals 36 in the socket 37.

The lower end of the handle 35 is threaded into a metallic collar 45 which in turn is threaded onto a member 46 forcibly driven on a metallic tube 47 surrounding the stem insulator 23. A flanged sleeve 48 having a slot extending through the flange and longitudinally thereof, fits over the metallic tube 47 and the insulating strip 31 which has a widened portion 39 (Fig. 1) extending through a slot in the tube 47 and the slot in the sleeve 48. The flange of the sleeve 48 bears against the end of the handle under the collar 45 and serves to rigidly interlock these members and prevent an accidental withdrawal of the insulating strip through the opening in the end of the handle. At the lower end of the metallic tube 47, a thimble 50 is forcibly driven thereon and has a threaded end on which is screwed a metal shell 51 encasing the heating element 10 and separated therefrom by a mica cylinder 52. A thin metal washer 53 is placed between the shoulder of the threaded part of the thimble 50 and the metal shell 51 screwed thereon. The washer is adapted to interlock the thimble and shell when the washer is driven into semi-circular slots 54 and 56 in the shell and thimble as shown in Fig. 6 of the drawing. The shell 51 also has a threaded circular opening 55 for receiving a heat conducting core 57 inserted inside the resistor supporting cylinder 12 and a copper soldering tip 58 which abuts against the end of the core 57. The contact between the core 57 and the soldering tip 58 expedites the conduction of heat from the heating element 10 to the soldering tip.

The soldering iron is compact and comprises relatively few parts, each of which is removable as a unit, so that with the above described construction it is an easy matter to replace any particular part or parts without discarding the entire iron. The ease and quickness with which the unit may be disassembled will be clearly apparent from the following description: To disassemble the soldering iron, the retaining cap 40 is detached from the handle and the electrical socket 37 removed therefrom. The handle 35 with its collar 45 may be unscrewed from the member 46 of the tubular assembly 47 and withdrawn over the insulating strip 31 and connectors 32. This gives access to the

screws 33 on the connectors so that the leads 11 can be released from under the screws, thereby permitting the removal of the insulating strip 31, connectors 32 and flanged sleeve 48. The metal shell 51 is removed by driving the washer 53 out of the slots 54 and 56 restoring it to its originally flat condition and unscrewing the shell from the thimble 50 carrying with it the heat conducting core 57 and soldering tip 58. The heating element 10 with its leads 11, supporting cylinder 12 and insulating cap 21 are pulled away from the stem insulator 23 which may be very easily removed from the tube 47. Any part can now be readily replaced and the iron can be expeditiously reassembled ready for use.

Although the invention as herein described and illustrated is particularly well adapted to an electric soldering iron, it should be understood that the invention is adaptable to other electrically heated devices and should be limited only by the scope of the appended claims.

What is claimed is:

1. In an electrical heating device, a heating means, a housing for the heating means having a slot, an element engaging the housing and provided with a slot, and a member interposed between the housing and the element and engaging the slots therein for interlocking the housing and the element.
2. In an electrical heating device, a heating element, leads for the element, a support for the heating element, a slotted insulating cap for the support having a depression, and an insulating stem provided with a passageway for guiding the leads received from the slots in the cap and having an end adapted to engage the depression in the insulating cap for interlocking the cap and stem.
3. In a heating device, a double grooved insulating cylinder, a looped heating element supported in the groove of the insulating cylinder, leads for the heating element, a slotted insulating cap for guiding the leads from the heating element and having a substantially rectangular shaped depression, a stem of refractory material having a substantially rectangular end adapted to fit into the depression in the cap for interlocking the stem and cap.
4. In an electrical soldering iron, a heat insulated handle, a heating element, leads for the heating element, means for guiding the leads of the heating element into the handle, a shouldered strip housed within the handle, and slotted means engaging the shoulders of the insulating strip for interlocking the guiding means thereto.
5. In an electrical soldering iron, a handle, a heating element, leads for the heating element, a slotted insulating means for guiding the leads into the handle, an insulating strip engaging the slot in the means for guiding

the leads, and terminals fastened to the insulating strip and extending out of the end of the handle adapted to be inserted into an electrical supply socket.

5 6. In a heating device, a handle, a heating unit insulated from and encasing a part to be heated, leads for the heating element, a slotted insulating cap for guiding the leads from the heating unit, a stem insulator having individual passageways for guiding the leads from the cap into the handle, an insulating strip having a widened portion, connectors fastened thereto for engaging the leads of the heating unit and extending out 10 of the end of the handle, a flanged sleeve having a slot engaging the widened portion of the insulating strip for interlocking the stem insulator, insulating strip and handle, a detachable electrical supply socket for engaging the connector protruding out of the handle, and a member for substantially covering the socket and threaded on the end of the handle for maintaining a rigid electrical contact between the supply socket and the 15 connectors.

7. In an electrical heating device, a handle, a heating element, leads for the heating element, means for guiding the leads into the handle, an insulating strip housed within the 20 handle, slotted means engaging the strip for interlocking the guiding means thereto, a detachable supply socket for connecting the leads to a source of electrical energy, and means substantially surrounding the socket 25 for maintaining a connection between the socket and the handle.

8. In an electrical heating device, a handle, a heating element having leads, a hous-

ing for the heating element having a slot, a stem for guiding the leads of the heating element into the handle, an element encircling the stem and having a slot, a member interposed between the housing and the encircling element and engaging the slots therein for interlocking the housing and the 40 encircling element, terminals housed within and protruding beyond the end of the handle for making contact with the leads to the heating element, an electrical supply socket for making a connection with the terminals, 45 and a cap engaging the socket adapted to be threaded over the end of the handle for preventing accidental disconnection of the supply socket from the heating terminals.

9. In an electrical heating device, a handle, a coiled heating element wound in a helix, leads for the heating element, a plurality of strands extending inside a plurality of the convolutions of the coiled heating element and twisted with a lead of the heating 50 element for increasing the strength and conductivity of the leads, a slotted insulating means for guiding the reinforced leads into the handle, an insulating strip engaging the slot in the means for guiding the leads, and 55 terminals fastened to the insulating strip and extending out of the end of the handle adapted to be inserted into an electrical supply socket.

In witness whereof, we hereunto subscribe 70 our names this 7 day of December A. D., 1927.
